UNITED STATES PATENT OFFICE

JOSEPH S. BRYLKA, OF DU BOIS, PENNSYLVANIA

WATER SLEIGH

Application filed September 26, 1929. Serial No. 395,403.

This invention relates to improvements in devices for walking on water commonly known as water sleds.

The primary object of this invention is to provide a device of the above mentioned character adapted to be strapped to the foot of the user, whereby a person may stand upright on the device and take steps forward in the water on the surface thereof.

10 A still further object of this invention, is to provide a device of the above mentioned character having longitudinal runners adapted to prevent lateral movement of the devices while in use.

15 A still further object of this invention is to provide a device having the above set forth objects in combination with means for increasing the traction of grip upon the water surface, said means being adjustable vertically relative to the buoyant member.

20 Other objects and advantages of the invention will become apparent during the course of the following description of the drawings forming a part of the specification in which Figure 1 is a top plan view of a pair of the water skates embodying this invention.

Figure 2 is a top plan view of one of the 30 water skates showing the parts more in detail.

Figure 3 is a side elevational view of the device showing the adjustable water displacing member, adjustably secured to the front 35 portion of the water skate.

Figure 4 is a longitudinal sectional view on lines 4-4 of Figure 2 illustrating the general contour of the water skate and showing one of the hinged runners.

40 Figure 5 is a bottom plan view of one of the skates illustrating the manner of holding the hinged runners in their operative or extended position.

Figure 6 is a transverse sectional view 45 taken on lines 6-6 of Figure 3 showing the longitudinal ribs or runners hinged to the water skate in their full position and their folded position indicated by the dotted lines, and Figure 7 is a fragmentary sectional view 50 illustrating more in detail the manner of

holding the longitudinal ribs in their extended position.

In the drawings forming a part of this specification and in which similar reference characters are employed to designate like parts throughout the same, attention is directed to the drawings wherein is shown a buoyant member in the form of an elongated tank comprising a bottom 5 and a top 6, both of which are pointed at the front 60 ends and slightly curved at the rear ends. Side walls 7 are adapted to space the bottom and top walls 5 and 6 respectively and are connected together to form an airtight container. A rear wall 8 connects the side 65 walls 7 and the bottom and top walls 5 and 6 respectively. An opening 9 may be formed in the top wall 6 of the buoyant member and may be closed by a screw threaded plug 10 in order to drain the buoyant member of its moisture. Also secured to the top wall 6 is a cross member 11 by rivets 12 as best illustrated in Figures 2, 3, and 4. A foot receptor 13 is secured to the top wall 6 and transverse member 11 by rivets 14 and the foot receptor 13 is formed with a vertical flange 15 for securely holding the user's foot from slippage. A fastening strap 16 is secured to an ear 17 on the foot receptor while a buckle 18 is secured to an 80 opposite ear 19 by means of a strap 20. The strap 16 may be passed around the user's foot at the arch portion thereof and the free end of the strap 16 may be fastened in the buckle 18.

85 A water displacing device 21 is of horse shoe shape in cross section or side elevation and is mounted on the front portion of the water skate by means of brackets 22 having extensions 23 adapted to be secured to the front portion of the water skate by welding or the like. Each of the supporting brackets 22 are provided with bolts 24 which pass through openings in the form of vertical slots 25 formed in spaced relation in the water displacing device 21, whereby the same may be raised or lowered relative to the water skate and may be locked in adjusted position by the locking bolts 24 as desired by the operator.

To each longitudinal edge of the bottom wall 5 is secured a rib or runner 26 secured in place by hinges 27 having one of their leaves 28 secured to the runner 26 and the other leaf 29 fastened to the bottom wall 5 by means of rivets or the like. The longitudinal ribs or runners 26 may be held in their extended position by means of a pair of axially screw threaded rods 30 and 31 joined together at their screw threaded portions by a nut 32. The screw threaded rod 30 provided with an eye 33 which passes through a screw eye 34 fastened to the inside of one of the runners 26. The other screw threaded rod 31 is provided with a spherical end 35 and an extension 36 adapted to pass through a screw eye 37. A socket plate 38 is mounted on the inner side of the opposite runner 26 for receiving the spherical end 35 of the screw threaded rod 31.

For consideration of the operation of the device it will readily be seen that the operator may strap one of the water skates to each foot by means of the straps 20 and 16 and by adjusting the water displacing member 21 to a desired position the operator may then literally walk upon the water by taking the usual steps, with first one foot and then the other foot. When it is desired to transport the water skates the water displacing device 21 may be slid into its dotted line position shown in Figure 3 and the runners 26 may be hinged upon their hinges 27 into the dotted line position shown in Figure 6 whereby both of the devices may be compacted into one compact unit.

It is to be understood that various changes in shape, size and arrangement of parts may be resorted to without departing from the spirit of the invention or the scope of the subjoined claims, such as joining the members together as by chains 5^a to prevent spreading apart when the devices are used as a water sleigh or aquaplane in being drawn over water.

Having thus described my invention, what I claim is:—

1. A water skate of the character described, comprising an elongated waterproof tank, being pointed at its front end and square at its rear end, a foot receptor mounted on the top wall of the waterproof tank, water displacing means mounted on the front or pointed end thereof, adapted for vertical sliding movement and runners on the bottom wall of the waterproof tank for preventing side slippage.

2. A water skate of the character described, comprising an elongated waterproof tank, being pointed at its front end and square at its rear end, a transverse plate secured to the top wall of the waterproof tank, a foot receptor secured to the transverse plate, means associated with the foot receptor for fastening about the foot of the

user, water displacing means associated with the front end of the waterproof tank, hinged runners depending from the sides of the waterproof tank and means for holding the longitudinal runners in their operative position.

3. A water skate of the character described, comprising an elongated waterproof tank, being pointed at its front end and square at its rear end, a transverse plate riveted to the top wall of the waterproof tank, a foot receptor mounted on the transverse plate, straps and buckles associated with the foot receptor for holding a person's foot in place, water displacing means associated with the pointed end of the waterproof tank for vertical sliding movement and hinged runners depending from the side walls of the waterproof tank for preventing lateral slippage.

4. A water skate of the character described, comprising a waterproof tank formed by a top wall and bottom wall having pointed ends at the front portion thereof and squared at the rear portions thereof, side walls connecting the top and bottom walls, a transverse plate riveted to the top wall of the waterproof tank, a foot receptor mounted on the transverse plate, a strap for fastening the user's foot in the foot receptor, a water displacing plate bent around the pointed end of the waterproof tank, means for allowing the vertical sliding movement of the water displacing plate, a runner depending from the longitudinal side walls of the waterproof tank, hinge connections between the longitudinal runners and the longitudinal side walls of the waterproof tank, and adjustable means for holding the longitudinal runners in their operative position whereby lateral slippage is prevented.

In testimony whereof I affix my signature.
JOSEPH S. BRYLKA.
